UNITED STATES PATENT OFFICE.

THOMAS DUNCAN, OF FORT WAYNE, INDIANA.

ELECTRIC METER.

SPECIFICATION forming part of Letters Patent No. 605,665, dated June 14, 1898.

Application filed August 6, 1897. Renewed May 18, 1898. Serial No. 681,090. (No model.)

To all whom it may concern:

Be it known that I, THOMAS DUNCAN, of Fort Wayne, in the county of Allen and State of Indiana, have invented certain new and useful Improvements in Electric Meters, of which the following is a specification.

This invention relates to alternating-current meters of that class in which a rotary armature is set in motion by the inductive action of two or more magnetic fields of differing phase; and it relates more particularly to that type of such meters in which the rotary armature is of annular or cylindrical form and the magnetic fields are set up by inductive agencies, of which part are placed inside of and part exterior to the armature.

The object of this invention is to improve the efficiency and practicability of meters of this class by increasing the torque due to any given current without increasing the energy consumed by the meter, and thus to render the action of the instrument more sensitive and accurate, especially under light loads, where friction and inertia ordinarily offer a serious disturbing influence. Such effective increase of torque, I have discovered, will result from an arrangement of the internal and external fields such as to increase the number of axes or centers of polarization due to said fields. For example, in a familiar form of meter having an annular armature, an external series field, and an internal field arranged with its axis at an angle to the axis of the series field (this arrangement being present in several of the meters now on the market) I have found that by providing an additional field arranged on an axis distinct from the axes of the other fields and so located that the axis of one field extends between two of the fields that are set up on the opposite side of the annular wall of the meter from the first field the torque may be nearly or quite doubled without any appreciable increase in the amount of energy consumed by the instrument and without in any way altering the drag. In one effective construction the exterior or series coils of a meter embodying this improvement are provided as in former constructions, while the coils of the interior fields are mounted upon the poles of a cross-shaped core arranged with its axes intersecting the axis of the series coils.

In the forms shown in my pending application, Serial No. 647,303, filed concurrently herewith, the coils of the several poles of said core are all positively energized by connections with the work-circuit. The present case is generally similar and shows an almost identical structure mechanically, but differs in having part of its inner coils closed circuits, which are inductively energized by the remaining inner coils that are connected in the work-circuit. The principal difference electrically due to this arrangement is that the inner fields are no longer in step with each other, as in the other application referred to, but the current in the closed circuit lags behind the current in the connected inner circuit, while the latter current, owing to the inductive action of the magnetic core, lags behind the current in the outer or series coils. In each case, however, the lag is less than ninety degrees, so that a different phase results along each axis of polarization, and rotation of the armature with a largely-increased torque is induced in consequence, and, as before stated, the efficiency and accuracy of the meter are greatly improved without adding materially to the cost of manufacture or maintenance.

In the accompanying drawings, Figure 1 is a front elevation of a coulomb or ampere-hour meter constructed in accordance with my invention, one of the fan-blades being broken away to better show the parts behind it. Fig. 2 is a sectional side elevation thereof. Fig. 3 is a top plan section of the meter. Fig. 4 is a perspective view of the inner fields and connections. Fig. 5 is a diagrammatic view showing the manner in which the meter is connected in circuit. Figs. 6 and 7 are similar views showing different methods of adjusting or calibrating the meter. Fig. 8 is a diagrammatic view showing the several axes of polarization. Fig. 9 illustrates a third method of speed adjustment. Fig. 10 shows a method of connecting the meter in a high-tension circuit. Fig. 11 shows a wattmeter connection. Fig. 12 shows a different form of winding for the wattmeter connection.

In said drawings, A designates the main frame of the meter, and A' an upward-extending transverse yoke which supports the registering train and the upper spindle-bearing.

B designates the annular armature, which is herein shown as comprising a cylindric rim or wall b and a top wall b', through the center of which the armature-spindle B' passes 5 and to which it is rigidly secured. The spindle B' is mounted to rotate freely in the usual manner and in the coulomb-meter shown is provided with attached fan-blades B², that operate as usual to afford a drag which varies 10 as the square of the speed. In a wattmeter such as is indicated in Figs. 11 and 12 this drag would obviously require to be replaced by a magnetic or other drag varying directly 15 as the speed.

15 C C designate the series coils, which are made of heavy wire and are designed to be connected in series in the work-circuit by means of binding-posts a, that are in this instance provided on insulating-blocks a' at the 20 back of the meter-frame. Said coils C are placed close together on opposite sides of the spindle B' and are enough larger than the armature to allow the latter to rotate freely within them. They are herein shown as fastened to a cross-bar A² by means of clamps c and screws c'. The bar A² rests upon the yoke A' just above the fan-blades B² and is 25 detachably secured in place by screws a².

Within the armature B is provided a magnetic core D, upon the poles of which two sets 30 of coils D' and D² are mounted. The coils D' are made of comparatively fine wire and in the coulomb-meter shown have their terminals d also connected with the binding-posts 35 a, so that they are in parallel with the coils C. The coils D² are closed circuits and may be conveniently made of copper loops or punchings slipped over the ends of the core D. The latter is preferably made of laminated iron 40 and of cross shape, with its two axes 1 1 and 2 2 arranged substantially at right angles to each other. The coils D' are shown as provided on the opposite poles of the core along the axis 1 1 and the closed circuits D² on the opposite 45 poles along the axis 2 2. Said axes 1 1 and 2 2 are arranged at angles of approximately forty-five degrees with the axis 3 3 of the coils C. For purposes of adjustment and calibration, however, it is frequently desirable to vary 50 these angles, and to this end the core is shown as adjustable about a vertical axis. The several laminæ of the core are in this instance secured upon the upper end of a tubular standard D³, which passes down between the 55 series coils and rests upon the cross-bar A². Said standard fits over and is capable of oscillation about a fixed centering-tube d', which is inserted in the aperture in the cross-bar through which the spindle B' passes and 60 loosely surrounds said spindle. A lever D⁴ is attached to the lower end of the standard D³ and is provided at its outer ends with an arc-shaped slot through which a clamping-screw d² is passed. By adjusting the lever D⁴ in 65 various positions within the limits of its slot the position of the inner core and fields may be varied with reference to the axis of the

series field to produce the speed adjustment desired. An additional or substitute means of adjustment is shown in Fig. 6, in which an inductance-coil I, having an adjustable core i, is inserted in the circuit of the coils D'. In Fig. 7 an adjustable non-inductive resistance R is inserted in the same manner to provide the necessary adjustment. This construction thus described will obviously produce fields of force along the three axes 1 1, 2 2, and 3 3, tending to polarize the armature and to set up Foucault or eddy currents, which will react to produce rotation owing to the phase 80 displacement between the fields. The series field will obviously be in step with the work-current; but the self-inductance due to the core D will cause the current in the inner coil D' to lag behind the work-current and the 85 current in the closed circuit D², resulting inductively from the coils D', will lag still farther behind. The lag will in each case, however, be less than ninety degrees, and the induced field along the axis 2 2 will therefore be out of step with both the other fields. 90

In Fig. 10 the meter, instead of being connected directly in the work-circuit, is inserted in a derived circuit energized by the transformer T, the primary of which is in series in the work-circuit. In Fig. 11 the inner coils D' are connected across the line or in shunt between the main leads of the work-circuit, so that the instrument will act as a wattmeter for measuring the energy consumed in the 100 work-circuit. A suitable drag, varying directly as the speed, will in this case be used in place of the fan-drag, as hereinbefore stated. Fig. 12 shows a somewhat similar arrangement in which the coils D' are divided 105 and connected partly in shunt between the main leads and partly in parallel with the series coils.

It will be understood that while the particular construction and angular arrangement 110 of the parts herein shown have been found to produce the best results thus far they are susceptible of various changes and rearrangements without departing from the spirit or 115 losing the advantages of the invention, which is accordingly broadly and specifically hereinafter claimed.

I claim as my invention—

1. An electric meter provided with an annular armature and a plurality of magnetic fields part of which are set up within and part without the armature, one field being on an axis extending between two other fields that are set up on separate axes on the opposite side of the annular wall of the armature from the first field, circuit connections energizing part of the fields with currents of differing phase, and means for inductively energizing the other part. 120

2. An electric meter provided with an annular armature and a plurality of coils part 125 of which are located within and part without the armature, one coil being arranged on an axis extending between two other coils that

are arranged on separate axes on the other side of the annular wall of the armature from the first coil, circuit connections for energizing two of the coils by currents of differing 5 phase, and means for inductively energizing the third coil.

3. An electric meter provided with an annular armature, a magnetic field set up exterior to the armature, upon an axis extending 10 between two fields set up within the armature upon separate axes, circuit connections for energizing the outer and one inner field by currents of differing phase, and means for inductively energizing the third field by a 15 current of still different phase.

4. An electric meter provided with an annular armature, coils exterior to the armature, coils within the armature, circuit connections for energizing said outer and inner 20 coils, a magnetic core having part of its poles inclosed by said inner coils, and closed circuits on the other poles of said core.

5. An electric meter provided with an annular armature, coils exterior to the armature, coils within the armature, circuit connections for energizing said outer and inner 25 coils by currents of differing phase, closed circuits within the armature apart from the first inner coil, and means for inductively energizing said closed circuits.

6. An electric meter provided with an annular armature, coils exterior to the armature connected in circuit, a cross-shaped magnetic core within the armature, coils on two 30 poles of the core, also connected in circuit and closed circuits on the other poles of the 35 core.

7. An electric meter provided with an annular armature, coils exterior to the armature, arranged upon an axis intersecting the latter and connected in circuit, a cross-shaped magnetic core arranged with its axes at an angle to the axis of the outer coils, coils on two poles of the core, also connected in circuit, and closed circuits on the other poles of 45 the core.

8. An electric meter provided with an annular armature, coils exterior to the armature arranged upon an axis intersecting the latter and connected in circuit, a cross-shaped 50 magnetic core within the armature arranged with its axes at an angle to the axis of the outer coils, coils on two poles of the core also connected in circuit, closed circuits on the other poles of the core, and means for adjusting the angular arrangement of the core with respect to the axis of the outer coils.

9. An electric meter provided with an annular armature, a series field exterior to the armature, a magnetic core within the armature made of cross shape with its axes intersecting each other and the axis of the series field at the center of the armature, coils on two opposite poles of the core connected in circuit, and closed circuits on the other two 60 poles of the core.

In testimony that I claim the foregoing as my invention I affix my signature, in presence of two subscribing witnesses, this 2d day of August, A D. 1897.
